UNITED STATES PATENT OFFICE.

MATTHIAS BROCK, OF BOSTON, MASSACHUSETTS, ASSIGNOR TO UNITED SHOE MANUFACTURING COMPANY, OF PATERSON, NEW JERSEY, A CORPORATION OF NEW JERSEY.

END-LASTING MECHANISM.

1,188,617.

Specification of Letters Patent. Patented June 27, 1916.

Original application filed June 29, 1912, Serial No. 706,655. Divided and this application filed July 9, 1915. Serial No. 38,913.

To all whom it may concern:

Be it known that I, MATTHIAS BROCK, a citizen of the United States, residing at Boston, in the county of Suffolk and State 5 of Massachusetts, have invented certain Improvements in End-Lasting Mechanism, of which the following description, in connection with the accompanying drawings, is a specification, like reference characters on the 10 drawings indicating like parts in the several figures.

This invention relates to end lasting mechanisms and has for its object to provide improved means for conforming upper 15 materials to the side faces of a last.

This application is a division of application Ser. No. 706,655, filed June 29, 1912, Lasting machines.

A feature of the invention consists in an 20 end embracing band and a support for the closed end of the band which is adjustable to position the band transversely. In the illustrated embodiment of the invention a heel embracing band is provided with a 25 support which is also adjustable to position the band longitudinally of a lasting head and relatively to heel lasting wipers.

A further feature of the invention consists in novel adjusting means constructed 30 and arranged for convenient operation in positioning an end embracing band and maintaining it in adjusted position.

Other features of the invention consist in novel characteristics of construction of a 35 heel embracing band.

These and other features of the invention, including certain more important details of construction and combinations of parts, will be understood from the following description 40 of the illustrated embodiment of the invention and will then be pointed out in the claims.

Figure 1 of the drawings is a perspective view of a heel embracing band mechanism 45 embodying this invention. Fig. 2 is a perspective view of a heel band embodying a feature of this invention. Fig. 3 shows the improved heel band mechanism incorporated in a heel lasting mechanism. Fig. 50 4 illustrates a use which will be explained.

The heel lasting carriage 2 is mounted on a support 4 and contains a heel post slide 5 operated by rack teeth and a pinion 6 through a hand wheel, not shown, to draw the heel post and the shoe thereon 55 backwardly into the heel lasting means. These means are supported in a head 10, which is connected to the carriage at 11, and comprise heel embracing wipers 12 and devices for operating the wipers, and a heel 60 embracing band mechanism.

The band mechanism includes a band 15, illustrated as embodying the invention defined in prior Patent No. 1,108,101, granted on my application August 18, 1914. This 65 band is molded to fit the sides of the shoe in accordance with a feature of the present invention, and is formed to present normally the lower edges of its opposite end portions appropriately nearer together than 70 the upper edges so that when it is closed by its operating means 16, 17, 18, 19, 20, Figs. 3 and 4, its lower edges engage the shoe first and the area of engagement spreads toward the upper edges of the band and the shoe 75 bottom. This results in working slack stock upwardly to the edge of the shoe and into the field of operation of the wipers. The lower portions of the band ends are made independently elastic, by recessing them at 80 14, to enable them to adapt themselves to the width of the last while the upper edges are brought into firm engagement with the shoe during the band closing operation. The band is also, in accordance with a feature 85 of this invention, formed to present an opening that is a little narrower than the width of the heel portion of the shoe and its inner face is formed of materials that produce friction against the shoe upper stock so that as the shoe on the heel post is drawn backwardly into the band by the rotation of pinion 6, the narrow band is caused to engage the upper frictionally at 90 the corners of the heel of the shoe and forwardly tension the upper tightly around the rear end of the last.

The front end portions of the band 15 are supported in proper vertical relation to the plane of action of the wipers 12 by the oper- 100

ating means 16 which for this purpose act through the band chain 22 and clips 23 depending from the chain. The chain is formed with a block 24 at the closed rear 5 end of the band and through this block the rear portion of the band is sustained in proper vertical relation to the wipers 12 by the head 26 of rod 25 which extends to the rear end of the lasting head. The rod 10 is threaded into head 26 and, being restrained from endwise movement in the lasting head 10, can be turned to adjust the band longitudinally in the lasting head relatively to the wipers.

15 The block 24 which supports the rear end of the band is mounted to slide on the head 26 of rod 25 and is connected through slide 27 and lever 28 with an adjuster 30. The adjuster is a rotatable rod restrained from 20 endwise movement and threaded into a block 32 which is pivotally connected with the lever 28. The lever is fulcrumed at 33 so that rotation of the threaded rod 30 will set and hold the band in adjusted position 25 transversely of the lasting head.

Having explained the nature of this invention and described a construction embodying the same, I claim as new and desire to secure by Letters Patent of the 30 United States:—

1. In a lasting machine, the combination with an end lasting head having end lasting wipers, and an end embracing band carried in the lasting head, of an adjuster 35 connected with the closed end of the band and adapted for manipulation to set the band transversely of the head relatively to the wipers.

2. In a machine of the class described, 40 the combination with a lasting head, and an end embracing band carried in the head, of a supporting slide connected with the closed end of the band and mounted for movement transversely of the head, a lever 45 connected with the slide, and an adjusting device connected with the lever and adapted to set and hold the band in adjusted position.

3. In a lasting machine, the combination 50 with an end lasting head having end lasting wipers, and an end embracing band carried in the lasting head, of means for adjusting the band longitudinally and transversely in the lasting head relatively to the 55 wipers.

4. In a lasting machine, the combination 60 with an end lasting head having end lasting wipers, and an end embracing band carried in the head, of an adjusting rod connected with the band and extending to the outer end of the lasting head and adapted for operation to set the band forwardly and backwardly in the lasting head with relation to the wipers.

5. In a machine of the class described, 65 the combination with a head, and an end embracing band carried in the head, of a supporting slide for the closed end of the band, means for adjusting said slide and band transversely of the head, a support 70 upon which such adjustment of the slide is made, and means connected with said support to adjust the band forwardly and backwardly in the head.

6. In a lasting machine, the combination 75 with a lasting head having end lasting wipers, of an end embracing band carried in the lasting head, and supporting means for the closed end of the band which is movable to adjust the band transversely of the 80 lasting head relatively to the wipers.

7. In a lasting machine, the combination with a lasting head having end lasting wipers, of an end embracing band carried 85 in the lasting head, a supporting slide for the band mounted for adjustment transversely of the lasting head and relatively to the wipers, and a support for the slide which is mounted for adjustment longitudinally of the lasting head relatively to the 90 wipers.

8. In a lasting machine, the combination with a lasting head having end lasting wipers, of an end embracing band carried 95 in the lasting head, and a support for the closed end of the band which is adjustable to position said end of the band transversely and longitudinally of the lasting head relatively to the wipers.

9. In a lasting machine, the combination 100 with an end lasting head having end lasting wipers, of an end embracing band adjustable transversely of the machine relatively to the wipers and means for holding the band in adjusted relation to the wipers. 105

10. In a lasting machine, the combination with an end lasting head having end lasting wipers, of an end embracing band, and means for adjusting the closed end of the band transversely of the machine relatively 110 to the wipers.

11. In a lasting machine, the combination with an end lasting head having end lasting wipers, of an end embracing band, 115 means for supporting the ends of the band, and means connected with the middle portion of the band for adjusting that portion of the band transversely of the machine relatively to the ends of the band and holding it in adjusted position.

12. In a lasting machine, the combination with an end lasting head having end lasting wipers and an end embracing band, of means for adjusting the band transversely of the machine relatively to the wipers and holding it in adjusted relation to the wipers. 125

13. In a lasting machine, the combination with a heel lasting head, of a heel embracing

band and means for operating the band, said band being formed with an opening narrower than the width of the heel portion of the shoe and having an inner face 5 of material that produces friction against shoe uppers, and means for drawing the shoe into said band to cause the narrow

band to engage the shoe frictionally at the corners of the heel and forwardly tension the upper tightly around the rear end of 10 the last, substantially as described.

In testimony whereof I have signed my name to this specification.

MATTHIAS BROCK.
